C. E. WOODVILLE

PORTABLE LIGHT

Filed June 13, 1921

Witness,

S. J. Mann.

Charles E. Woodville.

By Frank d. Belknap. A.M.

UNITED STATES PATENT OFFICE.

CHARLES E. WOODVILLE, OF CHICAGO, ILLINOIS.

PORTABLE LIGHT.

Application filed June 13, 1921. Serial No. 477,052.

To all whom it may concern:

Be it known that I, CHARLES E. WOODVILLE, a citizen of the United States, residing in the city of Chicago, county of Cook, and State of Illinois, have invented certain new and useful Improvements in Portable Lights, of which the following is a specification.

This invention relates to improvements in portable lights and refers more particularly to a rugged type of construction, particularly adapted for use in factories, railway shops, mines, garages and all types of outside construction work.

Among the salient objects of the invention are to provide a lamp construction which is waterproof and one which is adjustable vertically and in addition, a lamp which may be radiated axially so that the light may be turned in any direction; to provide a construction in which the light cord is insertable into the lower parts of the upper telescoping member, a construction which obviates the objectionable difficulties which attend the wear and deterioration to the insulation where the cord is moved up and down within the adjustable stand; to provide friction elements, both in the lamp sockets and in the vertical stand which permit the positioning of the stand in any convenient position so that the illumination may be more advantageously placed relative to the work to be done.

In the drawings:

Fig. 1 is a perspective view of the stand. Fig. 2 is a detail showing the vertically adjustable feature.

Fig. 3 is a fragmentary detail of the lamp socket construction.

Fig. 4 is a detail of the dish spring friction element used in connection with the lamp socket.

Referring in detail to the drawings, on the cast iron stand 1, which is fitted with a threaded stud 2 is secured a vertical tube 3. At its upper extremity is a collar 4 in which is fitted a set screw 5. Within this vertical tube is fitted a slidable sleeve 6. Within the sleeve 6 is a tubular rod 7 which is threaded at both ends, being screwed into a cap 8 at its lower extremity and into a nipple 9 connected to the switch 10 at its upper extremity. Fixedly attached to the upper end of this inner tubular rod 7 is an enlarged bearing flange 11 and a nut 12. Between the nut 12 and the nipple 9 is a washer 13.

At the lower extremity of the rod and between the lower cap 8 and the sleeve surrounding the inner rod is a split friction ring 14. The construction is such that the sleeve 6 is vertically adjustable in the outer tube 3 and may be set fixedly in any vertical position by means of the thumb screw 5. The inner rod being fixed with the sleeve as far as vertical movement is concerned, is however, axially rotatable on the top of the sleeve and on the lower split ring. The tension which is imposed on the split ring by screwing the rod 7 into the lower cap determines the friction which is produced in turning the inner rod or tube. The amount of this friction may be adjusted by turning the bearing flange 11 by hand or the nut 12, both of which are fixed to the inner rod or tube 7, and when turned draw the cap up closer to the sleeve, tending to draw the split ring together and increasing the friction between the inner sleeve and the inner rod or tube. This arrangement of the sleeve and inner tube permits the rotating of the inner tube which holds the switch and upper lamp without moving the lower stand 1, and the friction permits the positioning of the light at any desired place without allowing it to become misplaced due to free axial rotation. The switch 10 may be of any common type of electrical switch which is incased in a heavy waterproof casing, the light cord entering the switch through a stuffing box arrangement 15, which prevents any moisture, or water, entering the switch through the cord opening. An upper gooseneck 16 is screwed into an upper nipple 17 on the switch 10 and is so shaped as to centralize or stabilize the light. This gooseneck also furnishes a convenient handle for moving the light from place to place. To the upper extremity of the gooseneck which is threaded, is screwed a shouldered bushing 18. Crimped into the shoulder 19 of the bushing is a shell 20 which carries the lamp socket 21. Between the shell 20 and the outer casing 22 is a washer 23 and outside of the casing 22 is a friction dish spring 24 and a washer 25, the entire assembly being held rigidly in place by means of the locknut, 26, which is threaded to screw onto the threaded bushing. The wire connections which enter the switch through the stuffing box 15 and which comprise a durable, heavy, waterproof light cord 27, pass up inside of the

gooseneck and terminate in suitable connections in the socket. An electrical incandescent bulb 28 is screwed into the light socket 21. A reflector 29 of pressed steel and having an inner reflecting surface such as porcelain, is rigidly attached to the outer casing 22 and has a front lens which is protected by means of a convex wire grating. In place of the convex wire grating, a convex lens having wire molded in the glass to reinforce it, may be used. The lens is held in the reflector by means of a watertight rim 31.

The interposition of the dish spring 24 between the outer casing and the locknut permits the rotation of the reflector so that the light may be projected either up or down as the case requires. This rotation of the reflector in combination with the axial 20 rotation of the supporting rod allows the light to be projected in almost any direction from a single position.

When it is desired to work close to the floor, the stand may be separated by unscrewing the lower nipple of the switch 25 from the upper extremity of the inner rod or tube 7 and unscrewing the outer tube 3 from the threaded stud 2. The internally threaded nipple 9 may then be screwed directly onto the stud 2 of the stand 1, thereby shortening the stand to the extent of the length of the outer sleeve 3. The portable lamp which is ruggedly constructed to be used in connection with rough work such as 30 garage use or mine use is particularly adapted to work where the light will be subjected to moisture. It will be noted that all the

connections and light parts are made water-proof and that every provision has been made to prevent moisture from entering the stand. The friction elements mounted between the vertically adjustable tubes and the friction ring next to the lamp casing furnish means for quickly placing the light in any desired position. Another feature 45 of the lamp is that it may be readily disassembled and packed in a small container.

I claim as my invention:

1. A portable electric light comprising a base, an upright member detachably affixed thereto, a stem having a lamp and reflector mounted thereon, electric connections to the stem positioned exteriorly and independent of the upright member, said stem being adjustable in the upright member and rotatable in any adjusted position, and adapted to be affixed to the base with the removal of the upright member from the base, and the removal of the stem from the upright member.

2. A portable electric light comprising a base, an upright member detachably affixed thereto, a stem having a lamp and reflector mounted thereon, said stem adjustable in the upright member and having electric connections independent and exteriorly of the upright member, rotatable in any adjusted position, and adapted to be affixed to the base with its removal from the upright member, and the removal of the upright member from the base, said stem adapted to be locked against vertical displacement while being rotatable therein.

CHARLES E. WOODVILLE.
